UNITED STATES PATENT OFFICE.

SWEN A. PETERSSON, OF NEW YORK, N. Y.

FLOOR-PLANING MACHINE.

SPECIFICATION forming part of Letters Patent No. 599,531, dated February 22, 1898.

Application filed March 31, 1896. Serial No. 585,595. (No model.)

To all whom it may concern:

Be it known that I, SWEN A. PETERSSON, a citizen of the United States, and a resident of New York city, in the county and State of New York, have invented certain new and useful Improvements in Floor-Planing Machines, of which the following is a specification.

My invention consists of an improved contrivance of a rotary planing-tool and means for operating it on a truck movable about the floor for planing the surface of the floor, as hereinafter described, reference being made to the accompanying drawings, in which—

15 Figure 1 is a side elevation of my improved machine with a part broken out. Fig. 2 is a plan view with a part sectioned off horizontally. Fig. 3 is a detail in front elevation. Fig. 4 is a plan view of the planing-tool detached from the machine, and Fig. 5 is a side elevation of the planing-tool.

I provide a suitable truck, as the bed-frame *a*, mounted on small wheels *b*, on which it can be moved slowly over the floor to be planed, 25 and preferably gear one of the axles *c* of the truck with the shaft *d* of an electric motor *e*, mounted on the platform *g* to move the frame along as the work progresses, said motor being also employed to operate the planing-tool, 30 as will appear farther on.

The motor is to be provided with electric conductors adapted to connect with any available service-feeder and allow the machine to be moved about the floor.

35 For guiding the machine by the front axle *c'*, which is to be pivoted as usual in such trucks, a vertical shaft *h* is provided, having a hand-wheel *i* for turning it, with a cord or chain *j*, connected to a pulley *k* on the lower 40 end of the shaft and passing over guide-pulleys *l* to the ends of the axle, respectively, suitable for turning the machine according as the hand-wheel is turned one way or the other.

The planing-tool consists of a head-piece 45 *m*, having a shank *n*, adapted to be inserted in a socket in the lower end of a mandrel *o* and be secured by a set-screw in the common way of connecting such tools, said head being in this example of my invention made 50 with four plain sides, to each of which is attached a radially-projecting plane-bit *q*, having the proper inclination for planing the surface of the floor, and provided with the usual break-irons *s*, which radiate therefrom and 55 are formed integral with the head; but the

tool may be constructed with any approved number of bits. The tool-carrying mandrel *o* is mounted vertically in the extremities of two arms *t*, which are mounted on the vertical pivot *u* to swing from side to side of the 60 frame just back of the front axle. For thus swinging the planer a grooved hand-wheel *b'* is mounted on the top of the frame at the center of the front end, from which a cord *d'*, suitably coiled around it, extends in opposite 65 directions over guide-pulleys *e'* to the free end of one of the arms *t*, to which the ends of the cord are respectively connected suitably to swing the planing-tool as desired. The pivot *u* is also a rotating shaft, to which motion is communicated from the motor *e* by a belt *v*, and from which the mandrel *o* is driven by the belt *w*.

The mandrel *o* is vertically movable in its bearings in the arms *t* and at the upper end 75 coupled by the clutch *x* with the adjusting-screw *y*, carried in the yoke *z*, and having a hand-crank *a'* for working it to press the planer down to its work or raise it up, as required.

The truck-frame may of course be pushed along the floor by hand, or it may be geared with a hand-crank, so as to be moved by turning the crank.

I claim—

The combination in a floor-planing machine of the truck movable along the floor upon a hind axle in fixed bearings and a centrally-pivoted front axle, the floor-planing tool carried on the lower end of a vertical rotating mandrel located behind and in close proximity to the front axle, in horizontally-swinging supporting-arms and geared with motor apparatus located on the rear of the truck, the clutch and adjusting-screw on the 90 top of the mandrel, the shaft geared by the pulley on its lower end and a cord or chain with the ends of the front axle respectively for guiding the truck, and the hand-wheel and cord geared with the vibratory arms for causing the lateral movements of the planing-tool, all constructed and arranged substantially as described.

Signed at New York city, in the county and State of New York, this 15th day of February, 105 A. D. 1896.

SWEN A. PETERSSON.
